UNITED STATES PATENT OFFICE.

JAMES MURRAY, OF HILLSBOROUGH, OHIO.

PAPER-HOLDER.

SPECIFICATION forming part of Letters Patent No. 496,090, dated April 25, 1893.

Application filed August 25, 1892. Serial No. 444,072. (No model.)

To all whom it may concern:

Be it known that I, JAMES MURRAY, a citizen of the United States, residing at Hillsborough, in the county of Highland and State 5 of Ohio, have invented a new and useful Copy or Manuscript Holder, of which the following is a specification.

This invention relates to certain new and useful improvements in copy or manuscript 10 holders and has for its object to provide simple and convenient means for supporting copy or manuscript upon a suitable table, desk, or on a book in which the same is being transcribed, and in the latter instance acting as a 15 weight to hold the leaves of the book in position, and with this object in view the invention consists of the construction and arrangement of the parts as will be more fully hereinafter described and claimed.

20 In the drawings:—Figure 1 is a perspective view of the improved device shown as holding copies or manuscript in proper position. Fig. 2 is a transverse vertical section of the device. Fig. 3 is a detail perspective view of 25 the copy holding roller disconnected.

Similar numerals of reference are employed to indicate corresponding parts in the several figures.

Referring to the drawings the numeral 1 30 designates a weighted base from which rise standards 2 at opposite ends, having secured thereto on one side of the same a cylinder 3 with an opening 4 extending throughout the length of the same. Said cylinder 3 is open 35 at opposite ends and therein is rotatably and removably fitted a roller 5, having turn knobs or wheels 6, projecting from opposite ends thereof and beyond the ends of the said cylinder 3. Between the opposite ends of the 40 roller and the turn knobs or wheels, a space 7 is formed which will be more fully herein- after referred to. The said roller is formed with a longitudinally extending slot 8, and is cut away at the opposite ends adjacent to 45 said slot as at 9. Pivotedly connected adjacent to one of the ends of the roller and extending into the aforesaid slot is a clamping bar 10, which has the upper edge thereof bent at a right angle or approximately so as 50 at 11, which is adapted to fit into a cut away or grooved portion 12 in the roller adjacent to the slot thereof. The free end of the said

clamping bar 10 is adapted to engage a spring tongue 13 secured in the opposite cut away portion 9 of the roller and thereby tend to 55 hold the clamping strip in closed position. The manuscript sheets or copy to be transcribed is held in the slot of the roller by the clamping bar 10, and said roller rotated to display the lines of the manuscript or copy as 60 found desirable. In transcribing a number of documents which may be fastened together, the latter are first rolled up on the roller around the same which is necessary in view of the fact that the beginning of said document would be located next to the end where they are fastened. When copying from the 65 outer end of said form of papers, the said end is put in or fastened under the clamping bar and then copied as it is rolled up. 70

Secured to the uprights 2 is a cross bar 14 to the ends of which is pivotally connected or hinged a yoke 15 whose side arms fit in the recesses or spaces 7, between the turn knobs or wheels 6, in the adjacent end of the roller 75 to hold the latter in proper position and on the said yoke is adjustably mounted a slide 16 which is adapted to be employed to indicate or direct the attention of the copyist to the line to be copied and in very fine writing 80 or printing the said slide may be used to cover all of such matter except that desired to be copied at the time. When the manuscript is copied as it is rolled up, it is passed back under the cylinder so as to be out of the way 85 and is gradually rolled up and thus drawn in.

The entire device is very useful and convenient for all kinds of copying and where the copy is to be transcribed into a book the base 1 comes very successfully into play as a 90 weight to hold the leaves of the book as well as the book itself in proper position and also to conveniently locate the copy.

Having thus described the invention, what is claimed as new is— 95

1. In a copy or manuscript holder, the combination of a cylinder having an opening therein and a rotatable and removable roller mounted in said cylinder and having a clamping bar pivotally connected thereto, substantially as described. 100

2. In a copy or manuscript holder, the combination of a base having standards rising from the outer ends thereof, a cylinder se-

- cured to said standards and having an opening in one side thereof extending longitudinally of the same, a roller removably mounted in said cylinder and adapted to be rotated, 5 said roller having a slot therein extending longitudinally of the same, and a clamping bar hinged at one end to said roller and adapted to engage the longitudinal slot thereof to hold the copy or manuscript in position 10 and in connection therewith, substantially as described.
3. In a copy or manuscript holder, the combination of a base having uprights at opposite ends thereof, a cylinder secured to said 15 upright and having open ends at the front side, a roller removably and rotatably mounted in said cylinder and having a longitudinal slot therein and end turn-buttons or wheels, a clamping bar pivotally connected to one 20 end of said roller adapted to engage the said slot thereof and having the upper end bent

as set forth, and a tongue adjacent to the end of the roller opposite to that to which the clamping bar is pivoted and adapted to engage the free end of said clamping bar, substantially as described. 25

4. In a copy or manuscript holder, the combination with a rotatable roller having turn-knobs or wheels spaced apart from the ends thereof, and a yoke having a slide thereon 30 and pivotally mounted in position and adapted to have the ends thereof engage the spaces between the turn-knobs or wheels and the adjacent ends of the rollers, substantially as described. 35

In testimony that I claim the foregoing as my own I have hereto affixed my signature in the presence of two witnesses.

JAMES MURRAY.
